UNITED STATES PATENT OFFICE

GUST DEGAND, OF ST. BENEDICT, PENNSYLVANIA, ASSIGNOR, BY MESNE ASSIGNMENTS, TO REMBRANDT PEALE, OF ST. BENEDICT, PENNSYLVANIA, W. SANDERS DAVIES, OF NEW YORK, N. Y., AND WILLIAM S. WALLACE, OF PHILADELPHIA, PENNSYLVANIA, TRUSTEES

MATERIAL DISINTEGRATING AND CONVEYING MECHANISM

Application filed September 24, 1927. Serial No. 221,725.

The invention relates to novel and useful means for conveying wholly or partly disintegrated materials, and more especially to a novel and useful conveyor for shot-down coal, which is operated as an adjunct or attachment to any standard kerf-cutting mining machine.

Objects and advantages of the invention will be set forth in part hereinafter and in part will be obvious herefrom, or may be learned by practice with the invention, the same being realized and attained by means of the instrumentalities and combinations pointed out in the appended claims.

15 The invention consists in the novel parts, constructions, arrangements, combinations and improvements herein shown and described.

The accompanying drawings, referred to 20 herein and constituting a part hereof, illustrate one embodiment of the invention, and together with the description, serve to explain the principles of the invention.

Of the drawings:—

25 Fig. 1 is a top plan of a conveyor attached to a mining machine embodying the invention;

Fig. 2 is a side elevation corresponding to Fig. 1;

30 Fig. 3 is a central, transverse vertical section through the conveyor apparatus and the driving connection with the kerf-cutting machine, taken substantially on the line 3—3 of Fig. 2;

35 Fig. 4 is a transverse, vertical section of the combined machine, taken substantially along the line 4—4 of Fig. 1, with intermediate connecting parts broken away;

Fig. 5 is a transverse, vertical section 40 through the conveyor apparatus taken substantially on line 5—5 of Fig. 1; and

Fig. 6 is a longitudinal plan of the conveyor apparatus, with the top casing in section, taken substantially along the line 45 6—6 of Fig. 2, and having the central portion thereof broken away.

The invention is directed to providing a disintegrating and conveying mechanism for shot-down coal, to be connected to, driven 50 by, and traveled forwardly to its work, by

a mining or kerf-cutting machine, and it is adapted for work in even very thin seams. The actuating and driving mechanism of the mining machine is utilized, through proper connections to sump the conveyor 55 into the shot-down material, to further disintegrate it as may be necessary, to convey the so prepared material away from the face, and to progress the working conveyor forwardly progressively into the material operated upon.

The invention is further directed to providing conveying apparatus which can be quickly, easily, and firmly attached to the kerf-cutting machine for said purpose of 60 further breaking up and carrying away the material which has been shot down from the room face after being undercut by the kerf-cutter.

The invention not only provides for a 70 combination of mining machine and conveyor, but by such provision eliminates the necessity for a separate disintegrating and conveying machine, and prevents enforced idleness of the mining machine during the time that the shot-down coal is being carried away from the room face.

The invention provides a conveyor attachable to and detachable from a kerf-cutting machine, and which is carried on the work 80 side of the mining machine, the conveyor thereby engaging directly with the shot down material which is to be further disintegrated and conveyed away. For this purpose, the conveyor is provided with devices 85 which further disintegrate the material and impel it into the conveyor as the latter progresses or is sumped into the pile of shot-down material.

The usual practice in mining coal is to 90 under-cut the room face with a kerf-cutting machine and then shoot down the coal so that it may be carried away, usually by disintegrating and conveying machines. During the shooting and carrying away of the 95 shot-down coal, the mining machine is idle and is ordinarily taken out of the way, especially in low seam mines where space is essential. The separate disintegrating and conveying machines used for removing the 100

shot-down coal are very expensive and are themselves periodically idle during the under-cutting of the coal by the kerf-cutting machines.

5 The invention provides a traveling conveyor of very simple and comparatively inexpensive construction, adapted to be dumped into a pile of shot-down coal and provided with devices for disintegrating the shot-down coal and impelling it into the conveyor. The conveyor is constructed so that it can be readily and firmly attached to a standard kerf-cutting mining machine, the kerf-cutting machine acting to progress the conveyor to its work and to drive the moving parts of the conveyor. The kerf-cutting machine can thus be kept in continuous operation, while the expense and maintenance of a separate disintegrating and conveying machine are eliminated.

In the present preferred embodiment of the invention, a kerf-cutting machine of standard type is provided, having suitable driving mechanism and being equipped with the usual drums and cables for progressing and steering the machine. A traveling conveyor of the endless chain type, provided with flights for propelling the material, is adapted to be detachably secured to and extend along the advancing or working side of the kerf-cutting machine, whereby the advancing movement of the kerf-cutting machine, dumps the receiving side of the conveyor into the pile of shot-down coal. Driving sprockets for the conveyor chains are suitably connected to be driven by a driving shaft on the kerf-cutting machine. The advance conveyor chain is provided with disintegrating teeth or bits for further loosening the coal and impelling it into the conveyor.

Briefly stated, the operation of the above-described mechanism is as follows:—The independent mining machine or kerf-cutter is first operated in the usual well-known manner to undercut the room face. The undercut coal is shot-down, and the conveyor mechanism is then quickly and securely attached to the mining machine and the open side of the conveyor is dumped into the pile of shot-down coal by the lateral advancement of the kerf-cutting machine. Accordingly the coal loosened and disintegrated by the teeth, pours into the conveyor and is carried thereby to any suitable receiving and transporting means at the rear of the combined apparatus.

Other features of the invention will be first set forth in connection with the following detailed description, but it will be understood that the foregoing general description and the following detailed description are exemplary and explanatory but are not restrictive of the invention.

65 Referring now in detail to the embodiment

of the invention illustrated by way of example in the accompanying drawings, and referring primarily to the mining or kerf-cutting machine proper, a cutter arm 1 adapted to extend horizontally along the room floor is provided with an endless cutter chain 2 adapted to travel around the periphery of the cutter arm in a suitable channel 4 and having cutting bits or teeth 3.

70 A general box-like casing 5, from which the cutter arm and mechanism extend horizontally, is provided for containing and supporting the actuating and advancing mechanism of the kerf-cutting machine. Suitable motor and driving connections for actuating the cutter chain are located within the casing 5, it being understood that the machine is equipped with any suitable means for disconnecting the cutter chain drive from the motor while permitting the motor to continue in operation, all as in the usual practice.

75 Means are provided for progressing and controlling the direction of movement of the kerf-cutting machine. As embodied a cable winding drum 6 is mounted on the casing 5 and is driven by the motor through any suitable connections. A cable 7 wound on the drum 6 passes through a pulley or sheave 8 fastened near the forward edge of the casing 5, the sheave 8 serving to change the direction of the cable whose extending end may be fastened to suitable fixed means at some point in the room removed from the mining machine. As is well known in the art, the winding of the cable 7 on the drum 6 creates a tension along the extending cable and serves to progress or snub the mining machine. Suitable means for determining and controlling the direction of progression as embodied comprise a friction band steering drum 9, directing sheave 10 and cable 11 wound on the drum 9 and fastened through sheave 10 is fixed by suitable means elsewhere in the room. Since such drum and cable progressing and direction controlling means are well-known in the art further description of their operation here is considered unnecessary.

80 Referring now to the combined apparatus of the invention, comprising the kerf-cutting machine and a conveyor attached thereto, and more particularly to the means for attaching the conveyor to the kerf-cutting machine, as embodied the cutter arm 1 is provided with a centrally disposed and longitudinally extending slot or opening 12 which extends from a point within the casing 5 along the center of the cutter arm to a point a suitable distance from the forward end of said arm. A supporting and connecting bed plate 13 adapted to underly substantially the entire combined structure lies beneath the cutter arm throughout its entire length and extends laterally therefrom. An upwardly

120

125

130

projecting strip or flange 14 fast to the plate 13 is adapted to fit into a corresponding widened bottom portion of the slot 12 throughout the entire length of said slot 5 and has a narrower superimposed strip 15 welded to it to fit in the narrower portion of slot 12. Bolts 16 serve to secure the cutter arm 1 to the bed plate 13 at a plurality of points along the slot 12 by means of 10 straps 17 which bridge the slot 12 and are suitably apertured to receive bolts 16, strip 15 being provided with threaded apertures to receive the threaded portions of bolts 16, and correspondingly suitably threaded openings 15 in the strip 14 and the bed plate 13.

Spaced apart from the cutter arm 1 and extending parallel thereto a long box-like rectangular casing 17 for containing and supporting the conveyor mechanism is seated on 20 the bottom plate 13 and is secured thereto along its inner bottom edge by bolts 18 which pass through a flange lip on the casing 17. Inclined braces 19 attached to the bottom plate at 20 and to the rectangular casing 17 25 at 21 serve to support and further secure the casing 17 to the bottom plate 13. As embodied the casing 17 extends along the bottom plate 13 from the forward edge thereof, which is on a line parallel to the forward end of the cutter arm 1, to a line near the front wall of the casing 5 of the kerf-cutting machine, and thence inclines upwardly and rearwardly to a point above and behind the casing 5, as shown in Fig. 2.

30 The upwardly and rearwardly inclined portion of the casing 17 is provided with a bottom plate 54. The casing 17 is supported and detachably fastened to the casing 5 by plates 22 and 23 suitably attached to said 35 casing by tap bolts.

In carrying out the invention, suitable conveying means arranged along the exposed or advancing side of the combined apparatus are provided, which as embodied comprise 45 spaced apart endless chains 24 and 25 arranged within the casing 17 to form upper and lower runs following the top and bottom outlines of the casing and connected by a plurality of flat bars or flights 26 suitably 50 fastened to each chain and arranged along the chains in spaced apart parallel relation. At the forward end of the rectangular casing 17, the upper run of the conveyor is supported and directed by sprocket wheels 55 27 and 28 adapted to respectively engage chains 24 and 25 and suitably sleeved to rotate on a fixed shaft 29 which passes through both side walls of the casing 17 near the top thereof and is suitably supported by 60 a supporting bracket 30 fixed to the bottom plate 13 at 31 and extending upwardly therefrom. A stub shaft 32, fixedly mounted in the member 30 near the bottom of the casing 17 and in the same vertical plane as 65 shaft 29, serves to support a sprocket wheel

33 mounted to rotate thereon, the sprocket wheel 33 being adapted to engage the chain 24 at the commencement of its lower flight. The conveyor chains in their upper run are also supported at an intermediate point, 70 preferably along a line near the forward face of the casing 5 of the kerf-cutting machine, that is, where the casing 17 begins its upward inclination. As embodied, sprocket wheels 34 and 35 adapted to support and engage the chains 24 and 25 are fixed to a shaft 36 extending through the casing 17 below the upper run of the chains 24 and 25, said shaft being adapted to rotate in suitable bearings 37 and 38 attached 75 to the outer sides of the casings.

Supporting and guiding sprockets are arranged at the rear end of the casing 17 for engaging and controlling the movement of the chains as they pass the corners formed by the junction of the end wall 60 of the casing 17 with the top and bottom walls thereof. As embodied the sprocket wheels 39 and 40 engage with and support the upper runs of the chains 24 and 25, said sprocket wheels being mounted to rotate loosely on shaft 41, which passes through the side walls of the casing 17 and is held and supported by adjusting bolts 42 fixed in each end of the shaft and threaded in suitable supporting members 43 projecting from each side of the casing 17. A similar set of rotatably mounted sprocket wheels may be similarly mounted at the lower rear corner of the casing for engaging the lower run of the conveyor chains. The lower run of the conveyor is supported by the bed plate 13 along the horizontal section of its course and by the bottom plate 54 of casing 17 for the inclined section of the conveyor path.

In carrying out one feature of the invention driving means are provided for causing the conveyor chains and flights to travel around the casing in the direction indicated by the arrows in Fig. 2, said driving means preferably being connected with and actuated by the driving mechanism of the kerf-cutting machine. As embodied, a shaft 44 is mounted on the kerf-cutting machine by brackets 45 attached to the front wall of the casing 5, said shaft being rotated by suitable connections with the driving motor of the kerf-cutting machine. Shaft 44 is adapted to be detachably connected with the driving means of the conveyor. As embodied, shaft 44 is supported at the proper height and position to extend in prolongation of the center line of shaft 36 of the conveyor when the conveyor mechanism is attached to the kerf-cutting machine. A 110 suitable coupling for joining the ends of the shafts 36 and 44 is provided, which as embodied comprises flanged collars 46 and 46^a pinned respectively to the shafts 36 and 44. A plurality of pins 47 arranged in two con- 115 120 125 130

centric rows, extend from the collar 46 and are adapted to fit into corresponding holes in the collar 46^a, thereby providing means which can be readily connected and disconnected for rotatively locking the two collars.

In accordance with one feature of the invention, the advancing side of the conveyor is open to receive coal which slides into the conveyor due to the progressive broadside sumping movement given to the whole combined apparatus as it advances into the pile of coal. As embodied the side wall of the casing 17 is cut away from the front end 48 thereof to a line 49 a slight distance forward from the point where the conveyor casing begins its upward inclination, thereby exposing substantially the entire advancing side of the conveyor and permitting coal to easily enter the body of the casing and be engaged by the conveyor flights. As shown in Fig. 4 the top wall of the casing 17 extends downwardly and inwardly for a slight distance to form a protecting channel for the upper run of the conveyor chain 25. A further extension of the casing 17 is made at the forward upper corner 50 to provide protection for the sprocket wheel 28.

Referring now to that portion of the apparatus which serves to disintegrate or loosen the pile of shot-down coal which lies in the path of the advancing conveyor, as embodied each link of the conveyor chain 25 is provided with a disintegrating tooth or bit 51 which projects beyond the lower entering edge of the bed plate 13 as the chain moves along the entire exposed portion of the conveyor from the end 48 to the edge 49 of the casing 17. The bottom plate 13 is partly cut away at 52 to provide a path for the traveling disintegrating teeth. As the advancing side of the conveyor is sumped into the pile of shot-down coal, the teeth 51 loosen the coal ahead of the conveyor, breaking apart the larger lumps and impelling and increasing the flow of coal onto the conveyor.

It will be seen that no supporting shaft is provided for the chain 25 at the lower forward corner 53 of the conveyor casing, since a certain flexibility in the chain at this point is desirable, due to the fact that the chain is exposed to the inpouring coal. As a general rule the weight of the coal on the bottom run of the chains, combined with the rigidity given by the flights 26, serve to hold the chain 25 in position at this corner.

Means are provided for disposing of the coal picked up by the conveyor and carried along by the conveyor flights. As shown in Fig. 2 the upwardly inclined conveyor and casing 17 incline again towards the horizontal at a point beyond the rear of the kerf-cutting machine. An opening 55 is provided in the bottom 54 of the casing for the dumping of the coal carried to this point

by the conveyor. A downwardly projecting lip 56 serves to guide coal falling from the opening away from the body of the machine. It will readily be seen that coal carried by the flights 26 of the conveyor to the opening 55 will be there dumped or ejected into any suitable receiving means for transporting it away from the room.

The invention in its broader aspects is not limited to the specific mechanisms shown and described but departures may be made therefrom within the scope of the accompanying claims without departing from the principles of the invention and without sacrificing its chief advantages.

What I claim is:—

1. In a material disintegrating and conveying apparatus the combination of a flight conveyor having endless chains and flights connecting the chains and material disintegrating devices mounted on one of the conveyor chains adapted to project into a pile of material to disintegrate the material and impel it onto the conveyor when the conveyor is sumped into the material.

2. A conveyor for disintegrating and carrying away materials comprising endless chains, a plurality of flights connecting the chains, and material disintegrating devices mounted on the links of one of the chains to disintegrate material when the conveyor is sumped into a pile thereof.

3. An apparatus for disintegrating and conveying material including in combination a traveling flight conveyor comprising two endless chains and a plurality of material conveying flights connecting the chains and being exposed along one side to permit material to move onto the conveyor, means for progressing the conveyor laterally to sump the exposed side thereof into a pile of material and disintegrating devices mounted on the chain on the exposed side of the conveyor for disintegrating material and impelling it onto the conveyor.

4. A disintegrating and conveying apparatus adapted for use with a mining machine including in combination a travelling conveyor adapted to be sumped into a pile of shot-down material to gather and carry away said material, a bed plate on which the conveyor is supported and means for attaching the bed plate to the cutter arm of the mining machine for detachably connecting the conveyor to the mining machine.

5. A material disintegrating and conveying apparatus including in combination a travelling flight conveyor adapted to be sumped broadside into a pile of material, an open side on the conveyor for permitting the entry of material onto the conveyor, and means for closing the other side of the conveyor for preventing the material from being pushed off the conveyor without being carried away by the conveyor.

6. A material disintegrating and conveying apparatus including in combination a conveyor adapted to be dumped broadside into a pile of material, an open side on the 5 conveyor for permitting entry of material onto the conveyor, and a wall closing the other side of the conveyor for retaining the material on the conveyor until the conveyor moves it away.
- 10 7. A material disintegrating and conveying apparatus including in combination an endless conveyor adapted to be dumped into a pile of loose material and a frame for supporting and spacing the upper and lower 15 reaches of the endless conveyor a relatively great distance from each other, said frame having an open side permitting the entry of materials onto the lower reach of the conveyor.
- 20 8. A material disintegrating and conveying apparatus including in combination an endless flight conveyor adapted to be dumped into a pile of loose material, a frame supporting the endless conveyor and spacing the upper and lower reaches of the 25 conveyor a relatively great distance from each other, said frame having an open side permitting entry of material onto the lower reach of the conveyor and means for detachably attaching the frame of the conveyor to the cutter arm of a mining machine.
- 20 In testimony whereof, I have signed my name to this specification.

GUST DEGAND.
